UNITED STATES PATENT OFFICE

HAROLD O. BERRY, OF GARDNER, MASSACHUSETTS, AND WILLIAM T. BRADBURY, OF KANKAKEE, ILLINOIS, ASSIGNORS TO FLORENCE STOVE COMPANY, OF GARDNER, MASSACHUSETTS, A CORPORATION OF MASSACHUSETTS

DESIGN FOR A VALVE STAND FOR LIQUID FUEL BURNERS

Application filed September 8, 1932. Serial No. 44,783. Term of patent 7 years.

To all whom it may concern:

Be it known that we, HAROLD O. BERRY, a citizen of the United States, residing at Gardner, in the county of Worcester and State of Massachusetts, and WILLIAM T. BRADBURY, a citizen of the United States, residing at Kankakee, in the county of Kankakee and State of Illinois, have invented a new, original, and ornamental Design for Valve Stands for Liquid Fuel Burners, of which the following is a specification, ref-

erence being had to the accompanying drawing, forming part hereof.

The figure is a perspective view of a valve stand for liquid fuel burners embodying our design.

We claim:

The ornamental design for a valve stand for liquid fuel burners, substantially as shown.

HAROLD O. BERRY.
WILLIAM T. BRADBURY.
